Attorney

UNITED STATES PATENT OFFICE.

JOHN E. WEBSTER, OF FALLS CHURCH, VIRGINIA.

MUZZLE-CONTROLLING DEVICE FOR FIREARMS.

1,177,748.

Specification of Letters Patent.

Patented Apr. 4, 1916.

Application filed December 15, 1915. Serial No. 66,979.

To all whom it may concern:

Be it known that I, JOHN E. WEBSTER, a citizen of the United States, residing at Falls Church, in the county of Fairfax and 5 State of Virginia, have invented certain new and useful Improvements in Muzzle-Controlling Devices for Firearms, of which the following is a specification, reference being had to the accompanying drawings.

10 This invention has relation more particularly to a device of this general character especially designed and adapted for use in connection with pistols and it is an object of the invention to provide a novel and improved device of this type which serves to prevent the muzzle of a pistol from kicking upwardly and thus materially interfere with the effectiveness of the forearm.

It is also an object of the invention to 20 provide a novel and improved device of this general character which is engageable with the barrel of the fire arm at a point in advance of the trigger and adapted to be engaged by the hand grasping the pistol so 25 that the muzzle is prevented from kicking upwardly and whereby the entire forearm is employed in the maintenance of the pistol in its proper position in order to materially increase the steadiness of the aim.

30 The invention consists in the details of construction and in the combination and arrangement of the several parts of my improved muzzle controlling device for fire arms whereby certain important advantages 35 are attained and the device is rendered simpler, less expensive and otherwise more convenient and advantageous for use, all as will be hereinafter more fully set forth.

The novel features of the invention will 40 be carefully defined in the appended claims.

In order that my invention may be the better understood, I will now proceed to describe the same with reference to the accompanying drawing, wherein—

45 Figure 1 is a view in side elevation illustrating a pistol provided with an embodiment of my invention, a coacting hand being engaged by dotted lines; and Fig. 2 is a fragmentary view in elevation illustrating 50 a modified form of my invention.

As disclosed in Fig. 1, B denotes the barrel of the pistol and P the pistol butt or grip, both of which are of any ordinary or preferred construction, although it is preferred that the butt or grip P be of such a size as to permit the little finger of the hand

of the user to be free when the pistol is grasped by the hand.

As is particularly illustrated in Fig. 1, the barred B adjacent the muzzle thereof is 60 provided with the depending perforate ear 1 with which is operatively engaged the flexible member 2 capable of being lengthened or shortened as desired, as indicated at 65 3. By this arrangement it will be seen that 65 the flexible member 2 is substantially permanently attached to the barrel of the pistol. As any means may be employed for the lengthening or shortening of the flexible member 2, a detail description thereof is 70 believed to be unnecessary. As herein disclosed, the flexible member 2 passes through a ring 4 engaged with the ear 1, although it will be understood that if desired the flexible member 2 may be disposed directly 75 through the ear 1.

The outer or free end of the flexible member 2 has suitably secured thereto the annular member or ring 5 through which one of the digits, preferably the little finger, of the 80 hand of the user is adapted to be disposed, and whereby the muzzle end of the barrel is prevented from kicking up. It has also been fully demonstrated in practice that with the use of the flexible member 2 increased steadiness is afforded in aiming the fire arm as the 85 same is supported substantially by the entire forearm of the user. The annular member or ring 5 also serves to facilitate the insertion of a digit therethrough after the butt 90 or grip has been grasped by the hand as it will be readily perceived that it is only necessary to elevate the barrel B to cause the ring 5 and the flexible member 2 to swing inwardly.

In Fig. 2 of the drawings I illustrate an arrangement whereby my invention may be employed in connection with barrels which are not provided with a depending ear as has been particularly set forth with reference to Fig. 1 and as illustrated in Fig. 2, the rib 6 at the top of the barrel B' adjacent the muzzle thereof is provided with a transversely disposed opening 7 through which is directed the annular member or clip 8 embracing the barrel B' and provided at a point below the barrel with the eye 9 with which the flexible member 2^a is engaged, said member 2^a being also capable of lengthening or shortening and having its outer or free extremity provided with an annular member or ring 5^a for a purpose similar to that set 95 100 105 110 115

forth relative to the ring or annular member 5 shown in Fig. 1.

From the foregoing description, it is thought to be obvious that a muzzle controlling device for fire arms constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

- 20 1. In combination with the barrel of a fire arm, a flexible member permanently secured adjacent the muzzle end of the barrel of the fire arm, and of such a length as to terminate in close proximity to the free end of the grip 25 of the fire arm, and an annular member secured to the free end of the flexible member

through which a digit of the hand grasping the grip of the fire arm is adapted to be passed, said annular member serving to cause the flexible member to swing toward the grip 30 of the fire arm upon elevation of the muzzle end of the barrel.

2. In combination with the barrel of a pistol provided adjacent the muzzle end of the barrel with a perforate member, a flexible 35 member permanently secured to said perforate member and of such a length as to terminate in close proximity to the free end of the grip of the pistol, and an annular member secured to the free end of the flexible 40 member through which the little finger of the hand grasping the grip of the pistol is adapted to be passed, said annular member serving to cause the flexible member to swing 45 toward the grip of the pistol upon elevation of the muzzle end of the barrel.

In testimony whereof I hereunto affix my signature in the presence of two witnesses.

JOHN E. WEBSTER.

Witnesses:

W. E. LAWSON,
GEO. J. WEBER.
